UNITED STATES PATENT OFFICE.

ATTILIO MARIOTTI, OF FLORENCE, ITALY.

COMPRESSED-AIR HYDRAULIC PUMP.

1,155,594.

Specification of Letters Patent.

Patented Oct. 5, 1915.

Application filed March 30, 1914. Serial No. 828,203.

To all whom it may concern:

Be it known that I, ATTILIO MARIOTTI, subject of King of Italy, residing at Florence, Italy, have invented new and useful 5 Improvements in Compressed-Air Hydraulic Pumps, of which the following is a specification.

This apparatus serves for raising water or any other liquid, from any depth whatever. It is therefore specially applicable for mine shafts and may with great advantage replace ordinary suction pumps, or suction and force pumps, for while presenting none of the disadvantages of these latter, it offers very great advantages over them. In fact, it is always situated outside the shaft or well, no matter what the distance and the depth of the shaft or well may be; and, from this advantage it results: 15 that all damage can be repaired in the open; that a single shaft or well might, at the same time, serve for several buildings, and that a single pump might, at the same time, draw water from several shafts or wells.

20 The apparatus is illustrated in the accompanying drawings and is constructed and operates in the following manner:—

Figures 1 and 2 illustrates the complete apparatus fixed in position and Figs. 3 to 25 8 inclusive detail views thereof. It comprises: a double-acting compressor *a* (Fig. 1), a quick-acting reversing chest *b*, joined to the compressor, which serves for distributing and re-using the compressed air; two 30 cylindrical receptacles *c*, *d*, (Fig. 2) immersed in the liquid to be raised; two tubes *e*, *f*; which, through the chest *b*, place the compressor in communication with the receptacles *c*, *d*, and of a third tube *g*, by 35 which the liquid is raised and ejected. The compressor in the to and fro movement which is imparted thereto by suitable known organs (fly wheel *h*, connecting rod *i*, crank *k*, etc., Figs. 3, 4) draws in air alternately 40 through valves *l*, *m*; which through the tube *n* communicate with the chest *b*, and eject it in turn through the valves *o*, *p*, which 45 through the tube *q* common to both communicate also with the chest *b* (Figs. 4 and 5).

50 The quick-acting reversing chest illustrated in detail in Figs. 5, 6, 7 and 8, effects the principal essential operation, the characteristic of which is that of distributing 55 and simultaneously re-using the compressed

air. It is composed of four entirely distinct chambers *r*, *s*, *t*, *u*, (Fig. 6): the two central chambers *s*, *t*, communicate with one or other of the end chambers *r*, *u*, and that in an alternating manner, dependent upon the first position occupied by the two double seated valves *v*, *w*, for the operation of the organs which are situated in the chamber *u*. The movement of these valves is obtained by very rapid reversal effected in the following manner: The helicoidal gear wheel *x* is operated by a worm *y* (Fig. 4) keyed to one extremity of the crank shaft; at each revolution of the flywheel there will be a complete rotation of the worm and the 60 displacement of one tooth of the wheel *x*, which transmits its movement to the disk *z* (Fig. 6). This disk for one half of its circumference is of uniform level, while for the other half it recedes on an inclined 65 plane. The disk *z* in rotating with the wheel *x* will cause its pressure to be gradually exerted on the two small pins 1, 2, and consequently on the springs 3, 4, so that 70 while one spring will be already completely compressed and will remain so for 180°, the other will distend gradually, until after 180°, it will attain the maximum. At this moment, the small pin corresponding to the 75 spring which has remained entirely compressed for 180°, will be situated at that point of the disk *z* which descends from the maximum to the minimum level, and the spring will distend, causing the beam *5* (Figs. 6 and 7) to turn rapidly through a 80 given angle, and to thus displace the valves *v*, *w*. It is apparent that, under the rotation of the disk *z*, the effect will in the same 85 way be repeated, but in the reverse order, for the springs 3, 4, and, consequently for 90 the valves *v*, *w*; so that when the opening 6 is closed, 7 will be also closed, and 8 and 9 be open, and conversely. In order to prevent the movement of the disk *z* taking 95 place also in the opposite direction, a catch 100 17 (Fig. 6) is provided in a suitable position.

Now, from Fig. 2 it evidently follows that by submerging the receptacles *c*, *d*, in the liquid, the valves 10, 11, will be spontaneously raised, permitting the liquid to fill the receptacles, and through the valves 12, 13, to attain in the tube *g*, a level equal to that of the outer liquid. Under these conditions, when the compressor operates, the com- 110

pressed air, which through tube *g* (Fig. 4) passes to the distributing chest (Fig. 6), will arrive in chamber *t*, and by opening 9 will pass into the other chamber *r*, whence, through the opening 14 (Fig. 5) to which tube *e* (Figs. 1 and 2) is attached, it will reach the surface of the liquid in the receptacle *c*. It is evident that the liquid will be compelled to rise in the tube *g* to the same number of tenths of meters as there are atmospheric pressures attained by the compressor. During this period the suction valves *l*, *m*, (Fig. 4) which, through the tube *n* open into chamber *s*, will, through the opening 8, be in communication with the chamber *u*, which, through opening 15, (Fig. 5) to which tube *f* (Figs. 1 and 2) is connected, leads to the receptacle *d*. When the receptacles *c*, *d*, shall be both full of liquid, and this will take place on the first occasion only, the compressor will, through the tube *n*, draw in external air through the auxiliary valve 16 (Fig. 6) which opens into chamber *s*. During this period, the receptacle *c* will empty itself of liquid; but, with the movement of the compressor that of all the other organs will occur, including that of the worm *y* (Fig. 4), the wheel *x* and the disk *z* (Fig. 6) which act on the springs 3, 4. The number of teeth of the wheel *x* is calculated so that it will have completed a half rotation when one of the receptacles has been emptied of the liquid. But the disk *z* will, at the same time, have rotated 180°, so that the release of the spring, with the relative displacement of the valves *v*, *w*, will take place when one of the receptacles has been emptied of its liquid. It will therefore occur that the suction and compression passages will become reversed, because the communications of the two middle chambers with the two outer chambers will be inverted. But, as the receptacle which has been emptied of its liquid has remained filled with compressed air, this air will fill the chamber *s* (Fig. 6) and will fix the auxiliary valve 16; from this moment the compressor will no longer draw in air from the exterior, but that which finds itself confined in one or other of the receptacles *c*, *d*, with a manifestly great economy of motive power.

It is evident that this apparatus will also operate in tubular wells. We may, in fact, give to the cylindrical receptacles *c*, *d*, any capacity (it is only necessary that the number of teeth of the wheel *x* should be in accordance with such capacity), and they may be also of any diameter desired.

When the apparatus is intended for use for great depths (mines, &c.), as it will be necessary to employ high pressures and there will also be proportionate heating of the compressed air, the compressor will be composed of two cylinders in series, which

might be cooled by the water which has itself been drawn up and ejected.

What I claim as my invention, and desire to secure by Letters Patent, is—

1. In an apparatus of the class described, the combination of a pair of water reservoirs, a discharge for said reservoirs, a reversing valve chamber, having terminal compartments and a pair of intermediate compartments, each intermediate compartment having alining ports communicating with the terminal compartments, air pipes connecting the terminal compartments of the said valve chamber with the respective water reservoirs, a compressor, including the cylinder and a movable compressing element operating in the cylinder, a suction pipe connecting the cylinder with one intermediate compartment of the reversing valve chamber, a check valve provided in the suction pipe, a pipe for compressed air connecting the cylinder with the other intermediate compartment of the said valve chamber, a check valve provided in the last named pipe, a valve stem extending through each of the intermediate compartments of the reversing valve chamber and the alining ports thereof, a double headed valve plug mounted upon each stem within the corresponding intermediate compartment, the heads of each plug being adapted alternately to seat against the opposite ends of the receiving compartment to close the corresponding ports during movement of the stem, and means associated with the compressing element of the compressor for imparting movement in opposite directions to both valve stems of the reversing valve chamber at regular intervals during the operation of the compressor.

2. In an apparatus of the class described, the combination of a pair of water reservoirs, a discharge for said reservoirs, a reversing valve chamber, having terminal compartments and a pair of intermediate compartments, each intermediate compartment having alining ports communicating with the terminal compartments, air pipes connecting the terminal compartments of the said valve chamber with the respective water reservoirs, a compressor including a cylinder and a movable compressing element operating in the cylinder, a suction pipe connecting the cylinder with one intermediate compartment of the reversing valve chamber, a check valve provided in the suction pipe, a pipe for compressed air connecting the cylinder with the other intermediate compartment of the said valve chamber, a check valve provided in the last named pipe, a valve stem extending through each of the intermediate compartments of the reversing valve chamber and the alining ports thereof, a double headed valve plug mounted upon each stem within the corresponding intermediate compartment, the heads of each plug being adapted alternately to seat against the opposite ends of the receiving compartment to close the corresponding ports during movement of the stem, and means associated with the compressing element of the compressor for imparting movement in opposite directions to both valve stems of the reversing valve chamber at regular intervals during the operation of the compressor.

- plug being adapted alternately to seat against the opposite ends of the receiving compartments to close the corresponding ports during movement of the stem, a rocking beam pivotally mounted within one terminal compartment of the reversing valve chamber and having its ends pivotally connected with the valve stems, resilient means for normally maintaining the valve stems co-extensive with the plugs disposed in neutral position between seats, radial pins provided fixedly upon the valve stems, an operating shaft journaled in the valve chamber, a cam disk mounted fixedly upon the 15 said shaft within the chamber and having an annular flange provided with semi-arcuate, axially inclined cam faces for engagement with the said pins, and means connecting the said operating shaft with the 20 pressing element of the compressor for rotating the shaft synchronously with the operation of the said element.
3. In an apparatus of the class described, the combination of a pair of water reservoirs, a discharge for said reservoirs, a reversing valve chamber, having terminal compartments and a pair of intermediate compartments, each intermediate compartment having alining ports communicating 25 with the terminal compartments, air pipes connecting the terminal compartments of the said valve chamber with the respective water reservoirs, a compressor including a cylinder and a movable compressing element operating in the cylinder, a suction pipe connecting the cylinder with one intermediate compartment of the reversing valve chamber, a check valve provided in the suction pipe, a pipe for compressed air connecting 30 the cylinder with the other intermediate compartment of the said valve chamber, a valve chamber provided with a pair of receiving compartments, each receiving compartment having a valve stem extending through the valve chamber, a valve stem extending through each of the intermediate compartments of the reversing valve chamber and the alining ports thereof, 35 a double headed valve plug mounted upon each stem within the corresponding intermediate compartment, the heads of each plug being adapted alternately to seat against the opposite ends of the receiving 40 compartments to close the corresponding ports during movement of the stem, a rocking beam pivotally mounted within one terminal compartment of the reversing valve chamber and having its ends pivotally connected with the valve stems, resilient means for normally maintaining the valve stems 45 co-extensive with the plugs disposed in neutral position between seats, radial pins provided fixedly upon the valve stems, an operating shaft journaled in the valve chamber, a cam disk mounted fixedly upon the 50 said shaft within the chamber and having an annular flange provided with semi-arcuate, axially inclined cam faces for engagement 55 with the said pins, a gear wheel mounted loose upon the operating shaft, pawl and ratchet mechanism connecting the gear wheel with the shaft for rotation together in one direction, and means connecting the 60 gear wheel with the compressing element of the compressor for movement therewith.

In testimony whereof I have signed my name to this specification in the presence of two subscribing witnesses.
